UNITED STATES PATENT OFFICE.

HANS STAUGAARD AND GEORGE WATTS, OF DETROIT, MICHIGAN.

WINDOW SASH.

Application filed January 18, 1923. Serial No. 613,468.

To all whom it may concern:

Be it known that we, HANS STAUGAARD and GEORGE WATTS, citizens of the United States, and residents of Detroit, Wayne County, Michigan, have invented a new and Improved Window Sash, of which the following is a specification.

This invention relates to the construction of vertically slideable window sashes and the casings therefor, and its object is to provide a window construction of this character wherein the sashes may be swung inward on a horizontal axis from vertical to horizontal position so that the outside surfaces of the panes of said windows may be conveniently cleaned.

This invention consists in a window casing having vertical grooves in its opposed upright side members, a vertically slideable sash having grooves in alignment with the grooves in the casing and having pins at its lower end extending across the grooves in the sash into the grooves in the casing, a laterally movable guide bar in each groove in the sash and adapted to be moved into and out of the groove in the casing and having a hole at its lower end to receive the adjacent pin on the sash by which the guide bar is prevented from moving longitudinally relative to the sash, the guide bars having longitudinal grooves to receive the sash cords which attach to the pins at the lower ends of these guide bars.

It also consists in a vertically movable rod in each groove in the sash and guides therefor preventing lateral movement of the rod, and toggle links connecting the rod and the adjacent guide bar so that when the rod is moved up or down, the guide bar is moved out of or into the groove in the casing.

It also consists in a leaf spring attached to the casing at the bottom of each groove therein and near its lower end so that the spring may extend into the path of the adjacent pin on the sash, the spring being normally held out of this path by the adjacent guide bar, the spring serving, when the guide bar is withdrawn from the groove in the casing to permit the window to be swung to horizontal position, to prevent the sash cord from raising that end of the sash to which it is attached.

It further consists in the details of construction illustrated in the accompanying drawings and particularly pointed out in the claims.

In the accompanying drawings, Fig. 1 is a section of our improved window sash in a plane parallel to the glass therein and at the surface thereof. Figs. 2 to 6 inclusive 60 are sections on the lines 2-2, 3-3, 4-4, 5-5 and 6-6 respectively of Fig. 1.

Similar reference characters refer to like parts throughout the several views.

The window sash shown in the drawings 65 is generally of well known construction, having the transverse upper member 1, the transverse lower member 2 and the vertical side members or stiles 3. As shown in Figs. 4, 5 and 6, the outer edges of these stiles 70 3 are grooved to receive the metal shells 4, each consisting of the outer strips 5, the parallel inner strips 6, the middle strip 7 and the edge strips 8 between the strips 5 and 6. The channel formed by the strips 6 and 7 receives the guide bar 9 which is also preferably formed of sheet metal, this guide bar consisting of the sides 10 and the grooved edge 11. This guide bar 9 is laterally slideable between the side strips 6. 80 The ends 12 of the outer strips 5 may be folded in, as shown in Fig. 2 to lie against the transverse members of the sash.

Connected to the middle portion 7 of each shell is a pin 14, shown in Fig. 6, which 85 may be of any desired construction but we prefer to form the same with a reduced portion 15 which extends through a collar 16 seated in a proper hole in the lower end of the middle strip 7 of the shell and is held in 90 position by a nut 17 and any desired number of washers 18. The stile 3 is formed with a recess 19 to receive the nut and washers.

The grooved portion 11 of each guide bar is formed with a hole 20 to receive the pin 14 and this guide bar is therefore prevented from moving longitudinally in the channel formed in the metal shell 4, but it is permitted to move laterally into and out of the groove 22 in the portion 23 of the window casing stile. This portion 23 is shown to be a separate part of the window casing, but it is to be understood that the groove 22 may be formed in the well known upright portion 24 of the casing. Where new 105 window casings are installed in buildings the side members 24, or stiles, can be grooved, but where our improved windows are to be installed in buildings already provided with window casings, grooving of these 110 stiles 24 may present serious difficulties, so that it will usually be found advantageous

to secure grooved strips 23 to these upright side members of the window casings.

At any desired intervals along the bottom of the channel in the metal shell are secured the clips 26, shown in section in Fig. 5, within which the operating rod 27 is vertically slideable. This rod 27 is also preferably of sheet metal, although not necessarily so, and is movable up and down by means of a lever 28 having down-turned edges mounted on the pivot pin 29 carried by the sides 10 of the guide bar, as shown in Fig. 1. This lever also carries a pivot pin 30 extending across through the top of the operating bar 27 so that when this lever is swung up on the pivot 29 the operating bar 27 will be lifted.

Near the lower end of this operating bar is a pivot pin 31 which connects by means of the links 32 to the pivot pin 33 extending across between the sides 10 of the guide bar. When the lever 28 is swung up, the operating bar 27 will be moved upward and the guide bar 9 will be moved inward out of the groove 22 in the window casing. The lever 28 and the links 32 constitute toggle links which move the guide bar into and out of the adjacent groove 22 in the window casing. When entirely out of this groove, the sash may be swung on the pin 14 as a pivot to horizontal position, as indicated in Fig. 3, which permits the outer side of the pane 35 to be cleaned.

The sash cord 37 extends over the usual roller and connects to the usual weight, but such mechanism is omitted as it is well known in this art. A metal strip is formed into a loop 39 which receives the reduced portion 40 of the pin 14 at its lower end and has its upper end 42 secured to the sash cord, so that the sash weight and cord can assist in raising the window and hold it in any desired position.

When the sash is swung down to the horizontal position shown in Fig. 3, a large portion of the weight of the sash is taken from the sash cord so that the sash weight is liable to raise the end of the sash to which it is connected. In order to prevent this, we secure the upper end of a flat spring 43 to the stile of the window casing at the bottom of the groove 20 therein in any desired manner, screws 44 being shown. While the guide bar 9 is in the position shown in Figs. 1, 4, 5 and 6, the sash cords and weights operate in the usual manner, the spring 43 being pushed back out of the path of the pin 14. But when the guide bar is pulled inward so as to release the window sash from the casing, at which time the sash should be so low that the pin 14 is below the spring 43, this spring swings into the path of the pin 14 and prevents the lower end of the sash from being pulled up by the window cords. The

sash and its casing may be of any desired material and we do not wish to be limited to such articles made of wood.

It will be understood that this construction is duplicated at both sides of the window if desired and that the shells 4 may be omitted, if desired, the guide bars being mounted directly in grooves in the stiles of the sash. The invention permits the outsides of the panes to be cleaned at any time without interfering with exterior screens. Merely swinging the levers 28 causes the guide bars to move in and out. When a sash is to be removed from the casing, it is lowered until the pins 14 are below the springs 43. The guide bars are then drawn in by swinging up the levers and the sash is swung to horizontal position. One of the springs 43 is then pushed back to release the adjacent pin 14 which permits the sash to be lifted out of the casing and the sash cords to be disconnected.

The details of construction and the proportions of the parts may all be changed by those skilled in the art without departing from the spirit of our invention as set forth in the following claims.

We claim:—

1. In a window, the combination of a casing having vertical grooves, a sash mounted in the casing and having grooves in its side edges, guide bars mounted in the grooves in the sash and adapted to extend into the grooves in the casing, means to move the guide bars into and out of the grooves in the casing, pins extending from the sash, and a leaf spring mounted in a groove in the casing and adapted to have one end extend into the path of a pin on the sash, said spring being moved out of said path by the adjacent guide bar when said guide bar is in operative position in the groove in the casing.

2. In a window sash having side stiles and top and bottom rails, metal casings fitting over the edges of the stiles and provided with longitudinal grooves, guide bars mounted in said grooves and provided with longitudinal grooves to receive sash cords and with holes in their lower ends, a pin extending from the lower end of each stile through said hole in the adjacent guide bar and adapted to connect to the lower end of the adjacent sash cord, and means to move the guide bars into and out of the grooves in the casings consisting of vertically slideable rods, guides permitting longitudinal but preventing lateral movement thereof, links connecting the rods to the guide bars and means to move the rods longitudinally.

3. The combination of a window sash having longitudinal grooves in its upright edges, guide bars slidably mounted therein and having holes in their lower ends, pins

in said grooves and extending from the sash through holes in said guide bars to prevent longitudinal but permit lateral movement thereof and also adapted to connect to the 5 sash cords, and means to move the guide strips laterally, comprising a lever pivoted to one end of each guide bar, a rod connected to the lever and slideable longitudinally thereby, means to prevent lateral movement of the rod and toggle links connecting each rod and the adjacent guide bar.

4. The combination of a window sash having longitudinal grooves in its upright edges, guide bars slidably mounted therein 15 and having holes in their lower ends, pins in said grooves and extending from the sash through holes in said guide bars to prevent longitudinal but permit lateral movement thereof and also adapted to connect to the sash cords, and means to move the guide strips laterally, comprising a lever pivoted to one end of each guide bar, a rod connect- 20 ed to the lever and slideable longitudinally thereby, means to prevent lateral movement 25 of the rod and toggle links connecting each

rod and the adjacent guide bar, said guide bars having longitudinally grooved outer sides to receive the sash cords connected to said pins.

5. In a window, the combination of a cas- 30 ing having vertical grooves, a sash mounted in the casing and having grooves in its side edges, guide strips mounted in the grooves in the sash and adapted to extend into the grooves in the casing, means to move the guide bars into and out of the grooves in the casing, pins extending from the sash into the grooves in the casing and adapted to connect to the sash cords, said 35 guide bars having grooves to receive the sash cords, and a leaf spring mounted in a groove in the casing and adapted to have one end extend into the path of a pin on the sash, said spring being moved out of said path by the adjacent guide bar when 40 in operative position in the groove in the casing.

HANS STAUGAARD.
GEORGE WATTS.
